B.P. Milwaukee

UNITED STATES PATENT OFFICE

2,630,571

ELASTIC GIRDLE

Henry M. Herbener, Thomasville, Ga.

Application February 15, 1950, Serial No. 144,217

7 Claims. (Cl. 2—36)

1

My invention relates to girdles or like garments.

An important object of the invention is to provide resilient means to oppose the downward rolling of the upper edge of the girdle, and to present a large surface for preventing such rolling.

A further object of the invention is to provide a girdle of the above mentioned character which is comfortable and neat and attractive in appearance.

A further object of the invention is to provide a girdle of the above mentioned character which is of simplified construction and is cheap to manufacture.

Other objects and advantages of the invention will be apparent during the course of the following description.

The present application is a continuation-in-part of my co-pending application for Girdles, filed January 5, 1948, Serial Number 506.

In the accompanying drawings, forming a part of this application, and in which like numerals are employed to designate like parts throughout the same,

Figure 1 is a perspective view of a girdle embodying my invention,

Figure 1^a is an enlarged fragmentary front elevation of the body portion of the girdle, partly formed,

Figure 2 is a vertical section taken on line 2—2 of Figure 1,

Figure 3 is a horizontal section taken on line 3—3 of Figure 1,

Figure 4 is a side elevation of one of the hoops removed,

Figure 5 is a plan view of the same,

Figure 6 is an enlarged fragmentary front elevation of the body portion, partly formed, showing a modified form of hoop unit,

Figure 7 is a vertical section taken on line 7—7 of Figure 1,

Figure 8 is a fragmentary side elevation of the rear portion of the body portion, partly formed, showing a further modified form of hoop unit,

Figure 9 is a vertical section taken on line 9—9 of Figure 1.

In the drawings, where for the purpose of illustration are shown preferred examples of my invention, the numeral 10 designates the body portion of an elastic girdle which is unitary and formed of latex or the like. The body portion is accordingly horizontally and vertically elastic. The body portion is formed by dipping a core into a latex solution, and when a suitable number of

2

layers are built up a vertical group of resilient hoops 11 is applied to the body portion at the front thereof and held in place thereon by any suitable means. Each resilient hoop is preferably slightly under compression and its top and bottom are somewhat flattened and are connected by a flexible element or cord 12. The hoops 11 may be applied to the partly formed latex body portion before the same completely dries, so that the cords and hoops may adhere to such partly formed body portion and remain in place thereon. Any suitable means may be employed to hold the hoops in place upon the partly formed body portion. The hoops 11 are also formed horizontally 10 curved to correspond to the curvature of the body, Figure 5. The hoops are arranged in a vertical group in overlapping relation, as shown, and the top hoop is adjacent to the top edge of the body portion 10. After the group of hoops 11 is thus applied to the front of the partly formed body portion, the dipping of the form is continued and additional layers are built up to provide the completed body portion, and the hoops become embedded within the body portion and are integrally connected therewith.

Arranged upon opposite sides of the front group of hoops 11, upon or near the front of the body portion, are pairs of small hoops 13, adjacent to the upper edge of the body portion 10, Figures 1, 6 and 7. These hoops are preferably smaller than the hoops 11. The hoops 13 in each pair are spaced and substantially concentric, and are embedded in the body portion 10 in the same manner and by the same procedure as described in connection with the hoops 11. The hoops 13 are shown without the flexible cords 12, while the flexible cords 12 may be used with them, if desired.

Pairs of resilient hoops 14 are arranged adjacent to the top edge of the body portion 10 at or near the back of such body portion, Figures 1, 8 and 9. The hoops 14 in each pair are eccentric and their upper portions preferably contact and may be secured together by a sleeve 15, by welding, or other suitable means. The pairs of hoops 14 are embedded in the body portion 10 in the same manner and by the same procedure as described in connection with the hoops 11.

The hoops 11, 13 and 14 are resilient and are all preferably formed of piano wire.

This application is a continuation in part of my pending application for Girdles, Serial Number 506, filed January 5, 1948.

It is to be understood that the forms of my invention herewith shown and described are to

be taken as preferred embodiments of the same, and that various changes in the shape, size and arrangement of parts may be resorted to without departing from the spirit of the invention or the scope of the subjoined claims.

Having thus described my invention, I claim:

1. A girdle including a body encircling portion, said body encircling portion including a flexible part formed of sheet rubber having an upper end to be depressed by the movement of the wearer, said part being horizontally elastic, and a resilient hoop embedded in said part, said hoop including a closed top and a bottom and sides, the closed top being arranged adjacent to the upper end of said part to yieldingly oppose the downward movement of said upper end, the arrangement being such that when the upper end is moved downwardly the resilient hoop is vertically compressed and the sides moved outwardly from each other since said part is horizontally elastic.

2. A girdle including a body encircling portion, said body encircling portion including a flexible part formed of rubber having an upper end to be depressed by the movement of the wearer, said part being horizontally elastic, and a resilient hoop integrally connected with said part, said resilient hoop including a top and a bottom and sides, the top of the hoop being arranged adjacent to the upper end of said part to yieldingly oppose the downward movement of said upper end, the arrangement being such that when the upper end is moved downwardly the resilient hoop is vertically compressed and the sides moved outwardly from each other since said part is horizontally elastic.

3. A girdle including a body encircling portion, said body encircling portion including a horizontally elastic flexible part having an upper end to be depressed by the movement of the wearer, and a resilient frame including a closed top and bottom and sides which are secured to said part for movement therewith, the top being arranged adjacent to the upper end of said part to yieldingly oppose the downward movement of said upper end, the arrangement being such that when the upper end is moved downwardly the resilient frame is vertically compressed and the sides move outwardly from each other since said part is horizontally elastic.

4. A girdle comprising a body encircling portion formed of sheet rubber having an upper end to be depressed by the movement of the wearer, said body portion being horizontally elastic, and an upstanding resilient hoop including a top and bottom and sides embedded within the body encircling portion, said hoop being arranged at the front of the body encircling portion and the top of the hoop being arranged adjacent to said upper end to yieldingly oppose the downward movement

of said upper end, the arrangement being such that when the upper end is moved downwardly the resilient hoop is vertically compressed and the sides move outwardly from each other since the body receiving portion is horizontally elastic.

5. A girdle comprising a body encircling portion including a horizontally elastic front part formed of sheet rubber and having an upper end to be depressed by the movement of the wearer, and a plurality of upstanding resilient hoops embedded in the front part and arranged in a group, each hoop including a top and bottom and sides, at least one hoop having its top disposed adjacent to the upper end of said part to oppose its downward movement, the arrangement being such that the sides of each hoop move outwardly from each other when the hoop is vertically compressed.

6. A girdle comprising a body encircling portion formed of rubber and which is horizontally elastic and has an upper end to be depressed by the movement of the wearer, and a plurality of circumferentially spaced upstanding resilient hoops embedded in the body encircling portion, each hoop including a top and bottom and sides, the tops of the hoops being disposed adjacent to the upper end of the body encircling portion to oppose its downward movement, the arrangement being such that when each hoop is vertically compressed the sides of such hoop move outwardly from each other.

7. A girdle comprising a body encircling portion including a horizontally elastic section extending to the top of such portion, said section having an upper end to be depressed by the movement of the wearer, and a resilient upstanding hoop including a top and bottom and sides, the top of the hoop being arranged adjacent to the upper end of the section and the hoop being secured to said section at its top and bottom and sides.

HENRY M. HERBENER.
